Filed Aug. 26, 1960, Ser. No. 61,988

Term of patent 14 years

(Cl. D81—1)

FIG. 1 is a front elevational view of a combination heating and cooking unit embodying my new design.

FIG. 2 is an elevational view of the left hand side thereof, as seen in FIG. 1.

FIG. 3 is an elevational view of the right hand side thereof, as seen in FIG. 1.

FIG. 4 is a top plan view thereof the worm feed shaft is shown broken for the purposes of convenience of illustration only.

The dominant portions of the design are shown in full lines. The fragmentary showing of pipe elements in broken lines is for illustrative purposes only.

I claim:

The ornamental design for a combination heating and cooking unit, substantially as shown and described.
